UNITED STATES PATENT OFFICE.

JOHN MCRAVEN, OF LITTLE ROCK, ARKANSAS.

TYPE-WRITING MACHINE.

1,071,254.

Specification of Letters Patent. Patented Aug. 26, 1913.

Application filed August 28, 1911. Serial No. 446,395.

To all whom it may concern:

Be it known that I, JOHN MCRAVEN, a citizen of the United States, residing at Little Rock, in the county of Pulaski and State of Arkansas, have invented certain new and useful Improvements in Type-Writing Machines, of which the following is a specification containing a full, clear, and exact description, reference being had to the accompanying drawings, forming a part hereof.

My invention relates to an improved shift key mechanism and consists in the novel construction hereinafter described and pointed out in the appended claim.

The object of my invention is to provide an improved shift key mechanism, whereby a single set of keys may be used to control type-bars of both the upper and lower cases, thereby obviating the necessity of a large number of keys when separate type-bars are used for the upper and lower cases, and also obviating the necessity of placing the upper and lower case types on a single type-bar.

Referring to the drawings: Figure 1 is a plan view of a portion of a key-board of a typewriting machine having my invention applied thereto; Fig. 2 is a sectional side elevation of the same, the section being taken on the line 2-2 of Fig. 1; and Fig. 3 is a front elevation of two type-bars depending in normal position.

In carrying out my invention I may apply the same to any common typewriting machine now in use, making use of the usual frame 1, indicated by dotted lines in Fig. 1, and having the usual key-board 2 fitted with the usual set of keys 3. I have illustrated only the essential portions of the typewriting machine in order to economize in drafting space.

In practice there are the usual radially arranged set of type-bars 4 and 5 which carry respectively the lower and upper case types 6 and 7, said type-bars being pivotally mounted upon the frame 1 and connected by pull-rods 9 to the usual bell-cranks 10.

The numerals 11 and 11^a designate the upper and lower case horizontal pull-rods connected at one end to the said bell-cranks 10 and having on their opposite ends heads or shoulders 12 mounted to slide loosely in bearings formed in the frame piece 13. The stems of the keys 3 pass downwardly through openings in the key-board 2 and are connected at their lower ends to the usual bell-cranks 14. The horizontal shift-

ing pull-rods 15 have their front ends connected to said bell-cranks 14, while their inner ends are provided with heads or shoulders 16, corresponding in size and shape preferably to the size and shape of the heads or shoulders 12 carried by the said upper and lower case pull-rods 11 and 11^a. The said series of horizontal shift pull-rods 15 is not only adapted to slide axially, but their headed ends are adapted to be shifted up and down, to cause the heads thereon to engage with the corresponding heads of either the upper or lower case pull-rods 11 and 11^a in printing with the upper or lower case type-bars 4 and 5.

The numeral 17 indicates the shift key and the numeral 18 the shift key lever, which latter is fixed upon a rock-shaft 19 which has bearings 20 carried by the frame 75 of the typewriting machine so that, whenever said shift key 17 is depressed, the inner end of said shift key lever 18 will be correspondingly elevated and carry with it the inner ends of all of the shifting pull-rods 80 15. The numeral 21 indicates a guide-bar for the inner ends of said shifting pull-rods 15, to which the inner end of the said shift key lever is pivotally connected at 22.

The operation is as follows: It will 85 be understood that the key-board 2, the frame piece 13, the rock-shaft 19 and the guide-bar 21 extend a sufficient distance across the machine to accomplish the objects for which they are intended, above described. The guide-bar 21 should be heavy enough to return the shift pull-rods to their normal position, in contact with the lower case pull-rods 11^a, without the use of a spring, although it is clear that a skilled 95 workman may apply a spring for the purpose should he desire to do so, without departing from the spirit and scope of my invention. Upon pressing any one of the type-keys 3 its pull-rods will transmit the 100 necessary motion to the corresponding lower case type-bar 4, with the usual result that the type carried by said type-bar will make an impression stroke. When it is desired to use the upper case type-bars 5 and type 105 7, all that is necessary to do is to depress the shift key 17, by rocking the rock-shaft 19 and correspondingly elevating the guide-bar 21 and the inner ends of all of the shift key pull-rods 15, thus carrying upwardly 110 the heads 16 carried by said pull-rods, until said heads are in position to engage the cor-

responding heads 12 of the upper case pull rods 11, immediately above. After the last mentioned operation, depression of any of the keys 3 will operate the corresponding upper case type-bars 5. Upon releasing the shift key 17, the weight of the guide-bar 21 will immediately cause the heads 16 to resume their normal positions, just above the corresponding heads 12.

10. I claim:

In a typewriter, a frame, a pair of type bars pivotally secured to the frame, a vertical pull rod secured to each type bar, a

pair of horizontal pull rods arranged for the operation of the vertical pull rods, a head 15 on each of the horizontal pull rods, a guide bar, a pull rod carried by the guide bar and arranged for movements lengthwise through the guide bar, a head on said last mentioned pull rod, and a key for shifting said guide 20 bar, substantially as shown and for the purposes stated.

JOHN McRAVEN.
